GATE

Edward L. Ebaugh, Kneeland, Calif.

Application August 15, 1938, Serial No. 225,009

4 Claims. (Cl. 39—6)

This invention relates to improvements in gates and has particular reference to a self-opening and closing gate, that is, a gate wherein a vehicle passing therethrough will both open and close the gate during the act of passing.

A further object is to provide means whereby a person may manually open and close the gate during transit therethrough.

A further object is to produce a device of this character which is simple in construction, economical to manufacture, and easy to install.

Other objects and advantages will be apparent during the course of the following description.

In the accompanying drawings forming a part of this specification and in which like numerals are employed to designate like parts throughout the same,

Fig. 1 is a fragmentary top plan view showing my gate installed;

Fig. 2 is a longitudinal sectional view of the gate taken on the line 2—2 of Figure 1.

Fig. 3 is a cross sectional view taken on the line 3—3 of Fig. 1;

Fig. 4 is a cross sectional view taken on the line 4—4 of Fig. 3;

Fig. 5 is a fragmentary cross sectional view showing the gate partly tipped; and

Fig. 6 is a cross sectional view showing one of the manual actuating levers.

In certain parts of the country it is necessary to employ gates across highways so as to give access through fences; and in order that a vehicle may pass therethrough, it is necessary to dismount, open the gate, and remount the conveyance being used. This is often the case, particularly in the West where it is necessary to pass through a large number of gates in passing from one section of land to another. Of course, there is a great deal of delay experienced in opening and closing these gates.

I have, therefore, devised an arrangement wherein a person may pass through the gates without stopping the vehicle in which he is riding, or if on foot or horseback, he simply operates a lever conveniently arranged beside the roadway, and the gate will automatically open.

In the accompanying drawings wherein for the purpose of illustration is shown a preferred embodiment of my invention, the letter A represents a section of roadway adjacent the gate. In the present instance, I have shown this section as being formed of concrete. It is obvious, however, that any other supporting medium may be used, such as posts placed in the ground.

On each side of the roadway I mount vertical

supports 5 which are braced as shown at 6. As both supports carry the same operating mechanism, but one will be described. The support consists of a plate 7 having an arcuate shaped cam 8. Pivoted secured to the plate 7 above the cam 8 are two latch dogs 9 and 11 having their noses spaced apart a sufficient distance to allow for the entry therebetween of the gate bar extension 12. Each of these dogs has a horizontally disposed lip, as shown at 13 and 14 respectively. At 16 I have shown a horizontally disposed pivot bar, the top of which is flush with the roadway surface. This pivot bar has its ends overhanging recesses 17 formed at the sides of the roadway and serves to pivotally support the gate side plates 18, between which side plates the gate proper is secured, which gate is designated as a whole by the numeral 19.

In the surface of the highway I provide grooves 21 on both sides of the pivot bar 16, which grooves are spaced apart, corresponding to the spacing of the rails of the gate. Therefore, it is apparent that when the gate is swung downwardly about its pivots to either side of the pivot point, the rails of the gate will lie within the grooves so that the vehicle may pass thereover.

In order to swing the gate into its several positions, I provide an operating mechanism which comprises latch actuating sliders 22 (see Fig. 2) which are mounted parallel to the gate side plates 18 and have a hammer head cam 23 at their upper ends and cam slots 24 and 26 at their lower ends. The slot 27 permits vertical movement relative to the pivot bar 16, and the slot 28 permits vertical movement relative to the gate bar extension 12. By viewing Fig. 2 it will be noted that the hammer head cam 23 underlies the lips 13 and 14 of the dogs 19 and 11. Gravity ordinarily holds the latch slider in the position of Fig. 2, but as a safety factor I provide a spring 29.

In order to actuate the latch mechanism from a remote point, it is necessary to provide push and pull rods upon each side of the highway and extending in opposite directions from the gate. As the action of these pull rods is identical, but one will be described. Referring to Fig. 2, it will be noted that the pull rod 31 has its end extending through the cam slot 26 and also a cam slot 32 formed in the side plate of the gate. This pull rod 31 has its opposite end provided with a slotted eye 33 which rides upon a stud carried by a normally vertically disposed yoke 34 held in normal position by springs 36 and 37. This yoke 34 serves as an actuating bar and, therefore, ex-

tends across the highway so as to be contacted by an approaching car travelling in either direction.

If it is desired to actuate the gate manually, I may provide a manual hand operated lever at each side of the gate, as illustrated in Fig. 6, where it will be noted that the pull rod 31 has a hand lever 38 pivoted adjacent thereto and a spring actuated tongue 39 which normally does not extend across the slot 41. Extending through this slot 41 is one end of a yoke pin carried by the yoke 34. Therefore, by pushing the tongue 39 across the slot and moving the lever against the pin, the yoke will be moved in the direction of the applied power.

15 For instance, if the parts are in the position of Fig. 6 and the lever is moved toward the left of the drawing, a pull upon the pin will merely swing the yoke and allow it to slide in the eye 33. If the parts, however, are in the dotted line 20 position of this figure and movement of the lever is toward the right of the drawing, then the yoke pin will push against the rod 31 and perform the function of opening the gate away from the direction of the push.

25 The operation of my device is as follows:

Assuming that a vehicle approaches from the right of Fig. 3 and the wheels engage the yoke 34, movement will be transmitted through the pull rod 31 on opposite sides of the roadway, and 30 the ends of the pull rods will first ride up the cam slots 32 of the gate side plates 18 (see Fig. 2) and will cause the latch actuating slider 22 to move vertically, thus pushing the cam 23 against the lips 13 and 14 and releasing the dogs. 35 At the same time, the pull rods have moved above the axis of the pivot bar 16, about which the gate is hinged; and, therefore, the gate as a whole, now being released from the dogs 9 and 11, is free to move and will swing in the direction indicated in the full lines of Fig. 5, and the 40 rails of the gate will be at a point below the level of the roadway, whereby the vehicle may pass thereover without injury to the gate.

When the vehicle reaches the opposite side of 45 the gate and the wheels thereof impinge upon the next yoke, the result will be that the pull rods upon this side of the gate will now be moved toward the left of the drawing so that the far end of the eye will be in engagement with the yoke. Consequently, the vehicle passing over the 50 yoke will transmit a pull to the pull rods. As a consequence, the gate will be swung to vertical position. This last-mentioned pull rod is shown in dotted lines in Fig. 5, it being understood that the pull is toward the left of the drawing. As 55 the gate swings upwardly, the extension 12 will pass beneath one set of dogs and come to rest between both sets.

The manual operation of the gate is identical 60 with that just described.

It is to be understood that the form of my 65 invention herewith shown and described is to be taken as a preferred example of the same and that various changes relative to the material, size, shape and arrangement of parts may be resorted to without departing from the spirit of

the invention or the scope of the subjoined claims.

Having thus described my invention, I claim:

1. In a gate of the character described, a shaft 5 flush with the surface of the highway, a vertical standard on each side of the highway opposite the ends of the shaft, a gate above said shaft, vertically movable plates carried by the ends of the gate and pivotally mounted on the shaft, studs carried by the ends of the gate, latches 10 carried by the standards and engaging the studs and normally holding the gate in a vertical position, remote means operated by a vehicle for moving said plates vertically for releasing the latch, and oscillating them on the shaft for 15 swinging the gate down parallel with the highway.

2. In a gate of the character described, comprising a shaft flush with the surface of the highway, a vertical standard on each side of the 20 highway opposite the ends of the shaft, a gate above said shaft, vertically movable plates carried by the ends of the gate and pivotally mounted on the shaft, cam plates carried by the standards, studs carried by the ends of the 25 gate and travelling on said cam plates, latches resting on said cam plates and holding the studs against movement thereon with the gates in a vertical position, remote means operated by a vehicle for moving said plates vertically for releasing the latch and oscillating them on the shaft for swinging the gate down parallel with the highway.

3. A gate of the character described, comprising a shaft flush with the surface of the highway, 30 a vertical standard on each side of the highway opposite the ends of the shaft, a gate above said shaft, vertically movable plates carried by the ends of the gate and pivotally mounted on the shaft, studs carried by the ends of the gate, cam 35 plates carried by the standards upon which the studs rest, latches arranged on both sides of the studs for holding the gate in a vertical position, remote means operated by a vehicle for moving said plates vertically for releasing the 40 latches and oscillating them on the shaft for swinging the gate down parallel with the highway, and hand operated means connected to the remote control means whereby the same can be operated. 50

4. In a gate of the character described, comprising a shaft flush with the highway, a vertical standard on each side of the highway opposite the ends of the shaft, studs carried by the ends of the gate, vertically movable plates 55 mounted on the said studs and pivotally mounted on the shaft, a cam plate carried by the standards upon which the studs rest, latches arranged on both sides of the studs and resting on the cam plate for holding the gate in a vertical position, and remote means operated by a vehicle for moving said plates vertically under the latches and releasing the same and a continued movement of the remote operating means swinging the gate down parallel with the highway. 60

EDWARD L. EBAUGH.
